Patented Nov. 25, 1919.

INVENTOR

Eugene W. Keller
BY

ATTORNEY

UNITED STATES PATENT OFFICE.

EUGENE W. KELLER, OF NORTH BERGEN, NEW JERSEY.

EMBROIDERY-MACHINE.

1,323,066.

Specification of Letters Patent. Patented Nov. 25, 1919.

Application filed November 29, 1918. Serial No. 264,603.

To all whom it may concern:

Be it known that I, EUGENE W. KELLER, a citizen of the United States, and resident of North Bergen, in the county of Hudson 5 and State of New Jersey, have invented certain new and useful Improvements in Embroidery-Machines, of which the following is a specification.

This invention relates to embroidery machines and my improvement refers particularly to mechanical means whereby overlaid threads as of metal, wool, chenille, ribbon, lace, cording or the like may be incorporated in an embroidery design in the form of appliquéd work.

Usually appliquéd strands have been applied to embroidery by hand means, consuming considerable time, and occupying an undue share of attention from the operator.

Therefore my improvement is devised for the purpose of providing mechanical means for feeding appliquéd strands across the machine, in convenient position for engagement by the needle threads upon the surface of the goods being embroidered.

To this end I provide a number of frames, carrying spools having wound thereon the appliquéd thread, said frames being slidably mounted on guide rods, and having flexible connectors that are passed around pulleys located at opposite sides of the machine frame.

Means are also provided for moving said flexible connectors, first in one direction and then in the opposite direction, whereby an appliquéd strand, whose outer end is secured at one side of the machine frame, may be drawn in a straight line across the goods undergoing embroidering in the operation of the spool frame.

Other features and advantages of my said invention will hereinafter appear.

In the drawing:—

Figure 1 is a front elevation of a portion 45 of an embroidery machine provided with my improvement, and

Fig. 2 is an enlarged detail view of the spool, with its frame and operable means.

In the drawing an embroidery machine is 50 represented at 1—1, designating opposite side, upright members of the frame, and 2 indicates goods carried by the machine to be embroidered therein.

No needle bars or other elements of an ordinary embroidery machine are here shown, their character and arrangement being well

known to those skilled in the art, and because the present invention is confined to the means for presenting appliquéd strands operatively to the goods.

Horizontally extended across the machine frame are rods or wires 3—3 which are secured at their opposite ends to the frame members 1—1, as at 4, said rods or wires serving as guides for spool frames 5, that are mounted thereon to be slidable across the front of the goods. The frames are shown as each comprising a rectangle composed of the horizontal upper and lower bars 6, and vertical end bars 7, the latter having threaded hubs 8 to receive, respectively, alined set screws 9, that, at their inner ends are entered within the axial aperture through a spool 10, to revolvably support said spool in the frame. The frames 5 are each provided, 75 at opposite ends, with lugs 11—11, to which are engaged ends of a flexible connector, as a wire 12, the opposite end portions of the connector being passed around a series of four pulleys 13 which are located, two each 80 upon the side members 1 of the machine frame, in quadrangular arrangement, whereby the connector 12 is extended in two parallel lines across the face of the goods, and includes a spool frame in each line. The 85 location of the frames 5 in the said arrangement is such that when one frame is at one end of its line, the other frame is at the opposite end of its line. Consequently, in the movement of the connector about its 90 pulleys the respective frames 5 will move in opposite directions across the face of the goods. Movement may be imparted to the connector 12 by means of a pulley wheel 14, located at one side of the machine frame, 95 and wrapped with a double turn of said connector, said wheel 14 having an operating handle 15.

The spools 10 carry threads or strands 16 of material to form appliquéd work, one end 100 of the material from each spool being made fast to a side portion of the machine frame, as at 17. Then in the travel of a frame 5 carrying a spool across the face of the goods, a length of its strand 16 will be laid in position, to be engaged by the needle threads with the goods in the usual manner of performing appliquéd work.

Following this operation, as the goods move upwardly a desired extent in the 110 functioning of the embroidery machine, and a new position for an appliquéd strand is

presented upon the goods, the connector 12 may be given a reverse movement which will have the effect of releasing from the spool a further length of strand, laid in a line parallel to and below the former line. The operation is repeated in reverse succession as often as needed. It will be noted that by means of the oppositely located frames, 5, movable in different, parallel lines, two 10 strands of appliqué material are laid with each full operation of the connector in one direction.

The strand 16 leaving a spool is carried through an orifice 18 in the lower frame bar 15 6, which serves as a feed guide therefor.

Variations may be resorted to within the spirit and scope of my said invention and parts thereof used without others.

I claim:

- 20 1. An embroidery machine having a revoluble spool and mechanical means for laying an appliqué strand from said spool continuously across the surface of the work goods for the full width of the work, prior to the application of embroidery thereto along the line of said strand.
- 25 2. In an embroidery machine, in combination, a machine frame, a guide extended across said frame over the front of the goods therein, a spool carrying frame slideable upon said guide, a spool revoluble upon said spool frame, and mechanical means to move said spool frame along said guide, whereby an unstitched strand may be laid from the spool across the goods for the full width of the work, prior to the application of embroidery thereto along the line of said strand.
- 30 3. In an embroidery machine, in combination, a machine frame, parallel guides extended across said frame over the front of the goods
- 35
- 40

the goods thereon, a spool carrying frame slideable upon each guide, a spool revoluble upon each spool frame, and mechanical means to move said spool frames along said guides, whereby unstitched strands may respectively be laid from said spools across the goods for the full width of the work, prior to the application of embroidery thereto along the lines of said strands. 50

4. In an embroidery machine, in combination, a machine frame, a guide extended across the frame over the front of the goods therein, a spool carrying frame slideable upon said guide, a spool revoluble upon said spool frame, a flexible connector engaging said spool frame, pulleys supporting said connector, and means for actuating said connector to move said spool frame along said guide and thus to lay a strand from the spool in unstitched relation across the goods for the full width of the work, prior to the application of embroidery thereto along the line of said strand. 60

5. In an embroidery machine, in combination, a frame, parallel guides extended across said frame over the front of the goods therein, a spool carrying frame slideable upon each guide, a flexible connector engaging said spool frames, pulleys supporting said connector in rectangular arrangement, and a pulley wheel to actuate said connector, thereby moving the spool frames oppositely and enabling the spools to lay respective strands across the goods. 75

Signed at borough of Manhattan in the city, county and State of New York this 25th day of November A. D. 1918.

EUGENE W. KELLER.
